UNITED STATES PATENT OFFICE.

THOMAS PROCTOR, OF NELSON, ENGLAND.

VACUUM CLEANER.

Application filed April 24, 1925, Serial No. 25,649, and in Great Britain May 29, 1924. Renewed May 12, 1928.

The object of this invention is to provide a vacuum cleaner for domestic and other use which is hand operated, portable, readily usable, and effective in use. The invention relates to improvements in hand operated vacuum cleaning appliances of the type in which a pair of bellows are arranged at each side of a central box containing the dust receiver, the bellows being connected together by a suitable bar or rod so that they will work alternately, one pair of bellows drawing in air whilst the other pair is expelling it and operated by a handle affixed to one of the bellows and in which a second handle is affixed 10 to the central receptacle and the nozzle is carried at the end of a rigid tube attached to the underside of this receptacle, so that the bellows can be operated and at the same time the whole appliance can be moved over 15 the surface to be cleaned by the person operating it, or it can dwell over any particular spot without ceasing its continuous suction operation.

The present invention consists in a hand operated vacuum cleaning device of the type referred to in which the handles are arranged to be moved laterally, the movable handle is affixed to the bellows by a curved bracket, the air chamber and dust bag are open at the top 20 and closed by a lid which acts as a cap for the dust bag, the air chamber tapers towards the bottom and the dust bag is carried on a loose pipe with a flared end to fit over the fixed air pipe.

35 The invention will be described with reference to the accompanying drawings.

Fig. 1. Front view of the vacuum cleaner.

Fig. 2. Side view of same.

Fig. 3. Vertical section of same.

40 Fig. 4. Side view of dust bag.

Fig. 5. Plan of dust bag.

The vacuum cleaner is formed with a central receptacle A of rectangular shape in cross section, the sides *a* of which are inclined towards the bottom so that the area of the top of the receptacle is greater than the area of the bottom. A pair of bellows B B¹ is carried on each side of the receptacle A. Suction apertures *b* are formed in the walls *a* of the receptacle A through which the air is drawn when the bellows are being expanded and exhaust apertures *b*¹ are formed in the outer walls *b*² of the bellows through which the air escapes when the bellows are being contracted. The outer walls *b*² of each pair of bellows

are connected together by a bar or rod C pivoted at *c* *c*¹ to the walls so that as one pair of bellows is expanding the other pair is contracting and vice versa.

An operating handle D is carried in a bail *d* of approximately stirrup shape affixed to the outer walls *b*² of one or other of the bellows and a second handle E is carried in a bail *e* of approximately stirrup shape affixed to the receptacle A.

The bail *d* is bent inwards as shown to bring the handles D and E closer together. The nozzle F is carried on the end of a short rigid tube *f* which is connected by means of the bayonet joint *f*¹ to a second rigid tube *f*² projecting through the bottom of the receptacle A. The orifice *f*³ of the nozzle F is so arranged that when in use the handles will be moved laterally to and from each other.

The upper part of the receptacle A is closed by a lid or cover A¹ which can be readily removed for the removal of the dust bag G from the inside of the receptacle A. The lid A¹ also serves as a cap for the dust bag G which is made of suitable material to allow air to be drawn therethrough but prevent the passage of dust and dirt. It is attached at the upper end to a rectangular rigid frame H and at the lower end is provided with a ring or band *h*¹ of rubber adapted to fit over a tube H¹. The bottom end of the tube H¹ is flared so that it can be readily placed over or removed from the tube *f*² to which the nozzle carrying tube *f*¹ is affixed. The member H is supported on a ledge *a*² arranged in the receptacle A below the lid A¹ and is held by the lid when the latter is in position.

In operation the person using the vacuum cleaner holds the two handles D and E and imparts a to and fro lateral movement to one or both so that they are brought nearer together and then further apart. Since only the handle D is affixed to the bellows, one pair of bellows is contracted and then expanded and the other pair is expanded and then contracted so that a continuous suction is exerted by the nozzle on the surface being cleaned. As the handles D and E are being operated, the person using the machine can move it together with the nozzle over the surface to be cleaned, or can secure continuous suction over any particular spot.

I claim:

In a device of the character described, an elongated receptacle open at its top and hav-

ing downwardly converging walls, a pipe fixed in the lower end of said receptacle and carrying an elongated suction nozzle at its lower end, a second pipe having a flared lower end removably fitting over the upper end of said first mentioned pipe, a dust bag in said receptacle provided with an open upper end registering with the open end of said receptacle and having its lower end secured to 5 said second pipe adjacent the lower end there-

of, a removable lid closing the open top of said receptacle and of said dust bag, a pair of bellows in communication with said receptacle and mounted on opposite sides of said receptacle, the bellows being connected by a 15 rod for simultaneous operation, and handle means for operating said bellows.

In testimony whereof I affix my signature.

THOMAS PROCTOR.
